UNITED STATES PATENT OFFICE

WILLIAM L. CLOUSE, OF TIFFIN, OHIO, ASSIGNOR TO THE NATIONAL MACHINERY COMPANY, OF TIFFIN, OHIO

DESIGN FOR A PRESS

Application filed February 10, 1931. Serial No. 38,603. Term of patent 14 years.

To all whom it may concern:

Be it known that I, WILLIAM L. CLOUSE, a citizen of the United States, residing at Tiffin, in the county of Seneca and State of Ohio, have invented a new, original, and ornamental Design for a Press, of which the following is a specification, reference being had to the accompanying drawings, forming part thereof.

Figure 1 is a front elevation of the article showing my new design.

Figure 2 is an elevation of one side.

Figure 3 is an elevation of the opposite side.

Figure 4 is a rear elevation.

Figure 5 is a top plan view.

Figure 6 is a bottom plan view.

Some important characteristics of this design are the top and bottom clusters of projecting portions shown more particularly in Figures 5 and 6 as well as in Figures 3 and 4, the downward and rearward curvature of the top merging into the inclined back, as shown in Figure 1, the laterally spread sides as illustrated in Figure 4, and the forwardly bulged portion shown at the right of Figure 2 and in the upper central portion of Figure 1.

I claim:

The ornamental design for a press, as shown and described.

WILLIAM L. CLOUSE.
